UNITED STATES PATENT OFFICE.

BEN ZION HAUSNER, OF NEW YORK, N. Y.

SNAP-BUTTON.

1,179,915.

Specification of Letters Patent. Patented Apr. 18, 1916.

Application filed September 1, 1915. Serial No. 48,379.

To all whom it may concern:

Be it known that I, BEN ZION HAUSNER, a citizen of the United States, and a resident of New York, in the county and State of New York, have invented certain new and useful Improvements in Snap-Buttons, of which the following is a specification.

This invention relates to a snap button, which is of simple construction, possesses superior gripping power, and will retain its resiliency for a long period of time. The button is well adapted for use on garments, hangings, rugs, gloves and other articles.

In the accompanying drawing: Figure 1 is a plan of the female member of a snap button embodying my invention; Fig. 2 a plan of the male member; Fig. 3 a side view of the button, showing it open; Fig. 4 a section on line 4—4 Fig. 5; Fig. 5 a bottom view of the button showing it closed; Fig. 6 a bottom view of a modification, and Fig. 7 a section on line 7—7 Fig. 6.

The male member of the button consists of a rounded head 1, having a neck 2 and projecting from a plate 3 having thread holes 4, all as usual.

The female member of the button, to which my invention more particularly relates, is composed of a continuous length of wire or similar resilient material. This wire is so bent as to form a plurality of substantially U-shaped arches, each arch being composed of a pair of shanks 5, and a cross bar 6. The arches are so positioned, that all the shanks 5 are arranged in substantial parallelism with each other, and that any one arch is set at an angle to the adjoining arches, the first arch of the series joining the last arch, where the ends of the wire are soldered or otherwise connected. It is preferred to form the female member of four arches, as shown in which case, the arches will join each other at right angles. The two adjoining shanks of any two arches are by the construction described, placed in close proximity to each other and merge at their upper ends in a laterally and outwardly deflected loop 7, adapted to receive the thread by means of which the device may be stitched to the garment. These loops are arranged symmetrically with reference to said shanks and are contracted at the points of merger of the shanks into the loops. At their opposite ends, the cross bars 6, will form between them an opening

8, through which the head 1 of the male member is adapted to be projected. These cross bars, will all be located in a common plane, and each cross bar is made of convex form or deflected inwardly, so that the several cross bars will, with the quadruplex construction shown, form a polygon or figure with four arched sides. Each of these sides will however, not be directly attached to the adjoining sides, but by means of the intervening shanks 5, and thread loops 7, so that the resiliency of the entire length of wire is turned to practical account when pressure is exerted against the inner sides of the cross bars.

When the device is attached to the garment by the loops 7, the shanks 5 will stand off at right angles to the plane of the garment, while the cross bars 6 will be located in parallelism to said plane. If, in closing the button, the head 1 is pressed against arched cross bars 6, it will cause the several cross bars to be spread asunder, adjoining shanks of such cross bars, being during such operation, forced slightly apart. The strain to which the shanks are thus subjected will be transmitted to loops 7, and will thus cause said loops to open up so that in this way the resiliency of the entire length of wire is utilized. As soon as the head has cleared the cross bars, the arches will spring back into their original position, so that in this way they will tightly grasp neck 2, the grip thus obtained being considerably augmented owing to the convexity of the cross bars. In this position, the loops 7 will close at their mouths or points of merger into cross bars 6, the closing of the loops limiting the inward spring of the cross bars, so that in this way, the cross bars will grasp the shank of the male member with a constant and not undue pressure.

In Figs. 6 and 7, the device is shown to be adapted for use as a glove fastener. Here the loops 7, are incased within a flanged annular plate 9, provided with a socket 10, that extends a distance into the body of the device, between the shanks 5 thereof. This socket is adapted to receive a rivet 11, by means of which the device is adapted to be secured to the glove flap 12.

It will be seen that the button constructed as described, is simple in construction, possesses superior resilient qualities, and is not liable to become inert by protracted use.

I claim:

In a snap button, a female member composed of a continuous length of resilient material, formed into a group of arches, 5 said arches comprising cross bars arranged in a common plane, and a series of shanks arranged at an angle to said plane, the outer

ends of the several adjoining shank pairs merging into groups of laterally deflected loops that extend beyond the ends of the 10 shanks, the shanks adjacent to said loops being normally in contact to limit the inward spring of the arches.

BEN ZION HAUSNER.
